UNITED STATES PATENT OFFICE

157,028

ILLUMINABLE SEMAPHORE SIGNAL ARM
FOR AUTOMOTIVE VEHICLES

Louis W. Carlson, Port Orchard, Wash., assignor
to Vac-O-Lite Signal Co., Inc., a corporation
of Washington

Application August 28, 1948, Serial No. 148,352

Term of patent 14 years

(Cl. D72—1)

To all whom it may concern:

Be it known that I, Louis W. Carlson, a citizen of the United States and a resident of Port Orchard, in the county of Kitsap and the State of Washington, have invented a new, original, and ornamental Design for an Illuminable Semaphore Signal Arm for Automotive Vehicles, of which the following is a specification, reference being had to the accompanying drawings forming a part thereof.

In said drawings:

Figure 1 is an elevational view showing my new design of an illuminable semaphore signal arm for automotive vehicles.

Figure 2 is a top plan view thereof.

Figure 3 is a cross sectional view taken on the line 3—3 of Figure 1.

The drawing is shaded to indicate coloring.

The dominant features of my design reside in the portions indicated by means of full lines in the drawing.

What I claim is:

The ornamental design for an illuminable semaphore signal arm for automotive vehicles, as shown and described.

LOUIS W. CARLSON.
